UNITED STATES PATENT OFFICE.

HARRY C. WAYLAND, OF NEW YORK, N. Y.

COMBINED THROAT AND SMOKE-CHAMBER FOR FIREPLACES.

1,161,914.

Specification of Letters Patent. Patented Nov. 30, 1915.

Application filed May 21, 1914. Serial No. 839,968.

To all whom it may concern:

Be it known that I, HARRY C. WAYLAND, a citizen of the United States, residing in the city of New York, borough of Manhattan, county and State of New York, have invented new and useful Improvements in a Combined Throat and Smoke-Chamber for Fireplaces, of which the following is a specification.

10 My invention has for its principal object to provide means whereby the products of combustion arising from a fire place may be simply and efficiently conducted up through a chimney and so constructed that 15 a down draft exerted in the chimney and smoke chamber will not cause the smoke or gases to be impelled into the room in which the fire place is located.

20 A further object of my invention is to provide a complete unit which shall embody the several features comprising my invention in such fixed relation to each other as to prevent any error in installing the throat and smoke chamber in a chimney.

25 Those objects I accomplish by the means hereinafter described and illustrated in the accompanying drawings, wherein is shown a practical embodiment of my invention.

30 In the drawings, in which similar characters of reference indicate corresponding parts throughout the several views Figure 1 is a front elevation of a combined throat and smoke chamber applied to a fire place embodying my invention, the smoke chamber and stack of the chimney being partly shown in vertical section, the wall forming the front or breast of the fire place being partly broken away for that purpose. Fig. 35 2 is a vertical transverse section partly broken away, taken on the line 2—2 of Fig. 1. Fig. 3 is a horizontal section partly broken away, taken on the line 3—3 of Fig. 1.

40 As illustrated in the drawings, the lower portion 1 of the back of the fire place preferably extends in a vertical line or wall with the upper portion 2 inclined forward to aid in deflecting the heat from the fire place into the room in which it is located. The 45 side walls 3 of the fire place are preferably constructed so as to flare outwardly from the rear wall, as shown in Fig. 3. The up-

per part of the fire chamber comprising the rear walls and side walls terminates in a throat, having a front wall 4, and rear wall 5 said walls being inclined toward each other, and side walls 6 which are preferably constructed so as to incline inwardly toward each other, as is illustrated by dotted lines in Fig. 1, so as to make a contracted opening or connection between the fire chamber below said throat and a smoke chamber above said throat into which the throat terminates.

55 The smoke chamber is preferably constructed of a front wall 7, rear wall 8, and side walls 9. The front wall 7 at its junction with the front wall 4 of the throat, preferably curves forward and then upward, as illustrated in Fig. 2. And I prefer 60 to make said junction in the form of a shoulder 10. The rear wall 8 of the smoke chamber, at its junction with the rear wall 5 of the throat, extends backwardly from the throat and is preferably concaved or dished at 65 the floor 11 of the smoke chamber. As illustrated in Fig. 2, the junction between the rear wall 5 of the throat and the floor 11 of the smoke chamber may be, and in most instances is preferably, made slightly lower 70 than the junction between the front wall 4 of the throat and the front wall 7 of the smoke chamber. In such a construction if a 75 down draft be exerted in the chimney after or while the smoke from the fire place has passed from the fire chamber up into the smoke chamber, the down draft instead of forcing the smoke back through the throat and into the room, will strike the curved floor 11 of the smoke chamber and be deflected forward thereby, against the front wall 7 of the smoke chamber and upward 80 into the chimney, as indicated by the arrows in Fig. 2. The side walls 9 of the smoke chamber where they meet the side walls 6 85 of the throat, are also preferably curved laterally from their junction with the side walls of the smoke chamber, as shown by the lower portion 12 of said walls and indicated by dotted lines in Fig. 1. Those portions 90 of the side walls of the smoke chamber also tend to prevent the smoke from being blown back through the throat by a down draft in the chimney. Instead of so doing the smoke

impelled by the down draft will be deflected from a downward course and conducted toward the central portion of the smoke chamber so that it will be drawn upward into the chimney or stack in the manner already described in relation to the action of the front and rear wall of the smoke chamber.

A damper 13 may be mounted upon a pivotal rod 14 in suitable relation with the stack or chimney 15 and above the main portion of the smoke chamber. The damper may be of any suitable construction and may be controlled by a hand wheel or knob 16 extending laterally from the breast of the chimney, or it may be controlled by a rod extending forward in the well known form as commonly used.

A fire place having a throat and smoke chamber constructed in the manner illustrated and hereinbefore described, when in use, will readily permit the smoke and gases to pass upward through the throat into the smoke chamber and from the smoke chamber up through the chimney to the atmosphere. And even if a down draft be exerted in the chimney, the smoke and gases will not be thereby forced backward into the room, but on the contrary they will be deflected by said draft laterally and then forced upwardly and out of the chimney.

The throat and smoke chamber may be constructed of metal concrete or other suitable material, and is preferably constructed independently of the back and side walls of the fire place proper, and when placed in position on top of said walls the space between the throat and smoke chamber and the walls of the chimney and the wall of the building may be filled in with a mixture of concrete 17 or other similar material. In that way the throat and smoke chamber may be furnished to a builder complete and may be readily set in position by labor less skilful than would be required to determine and

construct the proper shape and proportions 45 of said chamber.

What I claim as new and desire to secure by Letters Patent is:

1. A combined throat and smoke chamber for fireplaces, the throat having front and rear walls inclined toward each other from their base upward, the smoke chamber having a front wall offset at its lower portion forwardly from its juncture with the front wall of the throat, and then inclined upward 55 and backward, a substantially vertical rear wall, and a concave deflecting surface between the rear wall and throat.

2. A combined throat and smoke chamber for fireplaces, the throat having front and rear walls inclined toward each other from their base upward, the smoke chamber having a front wall inclined forward from its juncture with the front wall of the throat and then upward and backward, a substantially vertical rear wall, a deflecting surface between the rear wall and throat, and end walls deflected laterally from their juncture with the throat and inclined upward toward each other.

3. A combined throat and smoke chamber for fireplaces, the throat having front and rear walls inclined toward each other from their base upward and oppositely disposed side walls inclined toward each other, the smoke chamber having a front wall inclined forwardly from its juncture with the front wall of the throat and then upward and backward, a substantially vertical rear wall, and a deflecting surface between the rear wall and said throat having its main portion arranged below the level of the juncture between the front wall of the smoke chamber and throat.

HARRY C. WAYLAND.
